UNITED STATES PATENT OFFICE.

GEORGE WILKINSON, OF PROVIDENCE, RHODE ISLAND, ASSIGNOR TO THE GORHAM MANUFACTURING COMPANY, OF SAME PLACE.

DESIGN FOR A SPOON.

SPECIFICATION forming part of Design No. 21,046, dated September 15, 1891.

Application filed July 2, 1891. Serial No. 398,318. Term of patent 7 years.

To all whom it may concern:

Be it known that I, GEORGE WILKINSON, a citizen of the United States, residing at Providence, in the county of Providence and State of Rhode Island, have invented and produced a new and original Design for the Ornamentation of the Handles of Spoons, Forks, &c.; and I do hereby declare the following specification, taken in connection with the accompanying drawing, forming a part of the same, to be a description thereof.

In the illustration a front or face view of a spoon is shown, the handle of which is ornamented with the design.

15 The design is arranged to follow the outline of the handle and is made up of the following elements: At the upper end or head of the handle A is located a leaf a, which extends down along the left-hand side of the handle. 20 Below this leaf a scroll b is located, and below this scroll a compound leaf-scroll c c is arranged. Below the scroll c c a partially-beaded scroll d is located, and below this a scroll e, which extends to the lower end of the handle. 25 On the right-hand side of the handle and below the leaf a a beaded scroll f is arranged, and below this a compound leaf-scroll g g. Below this compound scroll a leaf-

scroll h is located, and below this a scroll i, which extends to the lower end of the handle. 30 Upon the upper portion of the face of the handle and about midway between its edges a shield k is arranged, the edge or outline of which is composed of scrolls, and the field of which is ornamented.

35

What I claim as my invention, and desire to secure by Letters Patent, is—

1. In a design for the ornamentation of the handles of spoons, forks, &c., the leaf a, located at the upper end of the handle, and 40 the scrolls b c d e f g h i, extending upon the face downwardly from said leaf along the outline of the handle, substantially as described and shown.

2. In a design for the ornamentation of the 45 handles of spoons, forks, &c., the leaf a, located at the upper end of the handle, the scrolls b c d e f g h i, extending upon the face downwardly from said leaf along the outline of the handle, and the shield k, located upon 50 the upper portion of the face of the handle, substantially as described and shown.

GEORGE WILKINSON.
